COLLAPSIBLE CARTON

Kenneth T. Butterly, Kalamazoo, Mich., assignor
to Sutherland Paper Company, Kalamazoo,
Mich.

Application January 9, 1951, Serial No. 205,183

8 Claims. (Cl. 229—34)

1

This invention relates to improvements in collapsible cartons.

The main objects of this invention are:

First, to provide a carton which is well adapted for the packaging of confectionery, baked goods and the like and which supports the packaged articles so that they are not damaged or broken in merchandising.

Second, to provide a carton in which the articles packaged are supported out of contact with each other.

Third, to provide a collapsible carton with article holders which may be formed from an integrally cut and scored blank and one in which the article holders are springably retained in their erected position and also serve to brace and hold the carton walls in erected position.

Fourth, to provide a structure having these advantages which may be very economically produced.

Objects relating to details and economies of the invention will appear from the description to follow. The invention is pointed out in the claims.

A preferred embodiment of the invention is illustrated in the accompanying drawings, in which:

Fig. 1 is a perspective view of a package utilizing my carton and wrapped in transparent material, articles being illustrated in position therein by dotted lines.

Fig. 2 is a longitudinal section of the erected carton on a line corresponding to line 2—2 of Fig. 3.

Fig. 3 is a transverse section on a line corresponding to line 3—3 of Fig. 2.

Fig. 4 is a fragmentary perspective view of a corner of a carton illustrating the relation of certain parts and steps in erecting.

Fig. 5 is a fragmentary perspective view of the parts shown in Fig. 4 with the parts adjusted further to erected position.

Fig. 6 is an enlarged fragmentary view in section on a line corresponding to line 6—6 of Fig. 2.

Fig. 7 is a plan view of the blank.

Fig. 8 is a plan view of the collapsed carton.

For convenience in description, the terms side and end walls are used notwithstanding the fact that the carton illustrated is square. It will be understood that it may be of any desired dimension and the walls designated herein as end walls might be longer than the walls designated as side walls. The use of the terms side and end walls is believed to result in brevity.

2

The embodiment of my invention illustrated is formed of a blank of suitable carton stock cut and scored to provide a bottom 1, side walls 2—2 hingedly connected to the bottom by the hinging scores 3—3, and end walls 4—4 hingedly connected to the bottom by the hinging scores 5—5. The end walls are provided with holder member extensions 6 which are hingedly connected to the upper edges of the end walls by the scores 7—7. The end walls and the holder members are provided with integral corner flaps 8 hingedly connected to the ends of the end walls and holder members at 9, the hinging being desirably in the form of weakening perforations as distinguished from scoring and this is indicated in the drawing. In the preferred embodiment illustrated, the hinging lines 9 converge outwardly from the ends of the hinging scores 3.

The flap members 8 are provided with weakened folding lines 10 which are disposed in an inclined relation to the hinging scores 7 and divide the corner members into end wall flap sections 11 and holder member flap sections 12. The holder member flap sections have diagonal weakened folding lines 13. The side walls have diagonal weakened folding lines 14 extending from their end edges diagonally outward and providing hinging flaps 15 to which the corner flap sections 11 of the corner flap members are secured, desirably by adhesive, as indicated at 16 in Fig. 6. With the parts thus arranged the side walls may be folded inwardly upon the bottom and the end walls and their extending holder members folded upon the collapsed side walls.

To erect the carton from its collapsed position as shown in Fig. 8, it is grasped at its ends and pressure of the thumb applied to the holder members will swing the end walls to erected position and the holder members into the inwardly inclined position resting upon the bottom as shown in Figs. 2 and 3. Owing to the arrangement of the hinging or folding scores for the corner members, there is a springable snap-like action when the holder members are swung to erected position which acts to hold the holder members in erected position and the holder members serve to brace and support the walls in erected position.

The embodiment of my invention illustrated is designed to package confections such as indicated at 17, Eskimo Pies, for example, having sticks 18. The holder members are provided with edge recesses 19 and 20, the recesses 20 being out of alignment with the recesses 19. These recesses 55 are designed to receive the end of the packaged

article 17. The holder members are also provided with U-shaped slits 21 which are aligned with recesses of opposite walls and are adapted to receive the ends of the sticks 18. In packaging, the sticks are inserted in the openings 21 and the article 17 dropped into the notches. The carton is then desirably provided with a transparent wrapper 22 although it may be placed in a sleeve type of cover, or a telescoping cover may be provided as desired.

I have illustrated and described my invention in a highly practical embodiment. I have not attempted to illustrate or describe various other embodiments which I contemplate as it is believed that this disclosure will enable those skilled in the art to embody or adapt my invention as may be desired.

Having thus described my invention, what I claim as new and desire to secure by Letters Patent is:

1. A collapsible carton formed of a cut and scored blank and comprising a bottom, side and end walls hingedly connected to the bottom, article holder members hingedly connected to the outer edges of the end walls and of a width exceeding that of the end walls, and integral corner flaps hingedly connected to the ends of the end walls and holder members, the hinge connections for said corner flap members extending in outwardly converging relation from the hinging scores of the side walls to the bottom, the corner flap members having folding scores extending from the hinging scores of the holder members to the end walls to the end edges of the corner flap members and disposed in an inwardly inclined relation thereto, the sections of the corner flaps connected to the holder members having folding scores extending diagonally outward from the hinge connections for the holder members to the end walls, the side walls having folding scores extending diagonally outwardly from their end edges providing folding flaps to which the end wall sections of the corner flaps are secured permitting the side walls being collapsed inwardly upon the bottom and the end walls and holder members collapsed on the side walls, the holder members being provided with nonaligning article receiving recesses in their edges and with article receiving openings aligned with the recesses of the opposite holder member, the article holder members when the carton is erected being springably foldable to an inwardly inclined position between the side walls with their swinging edges on the bottom and acting to hold the carton in erected position.

2. A collapsible carton formed of a cut and scored blank and comprising a bottom, side and end walls hingedly connected to the bottom, article holder members hingedly connected to the outer edges of the end walls and of a width exceeding that of the end walls, and integral corner flaps hingedly connected to the ends of the end walls and holder members, the corner flap members having folding scores extending from the hinging scores of the holder members to the end walls to the end edges of the corner flap members, the sections of the corner flaps connected to the holder members having folding scores extending diagonally outward from the hinge connections for the holder members to the end walls, the side walls having folding scores extending diagonally outwardly from their end edges providing folding flaps to which the end wall sections of the corner flaps are secured permitting the side walls being collapsed inwardly upon the bottom and the end walls and holder members collapsed on the side walls, the article holder members when the carton is erected being foldable inwardly between the side walls with their swinging edges on the bottom and acting to hold the carton in erected position.

3. A collapsible carton formed of a cut and scored blank and comprising a bottom, side and end walls hingedly connected to the bottom, article holder members hingedly connected to the outer edges of the end walls and of a width exceeding that of the end walls, and integral corner flaps hingedly connected to the ends of the end walls and holder members, the hinge connections for said corner flap members extending in outwardly converging relation from the hinging scores of the side walls to the bottom, the corner flap members having folding scores extending from the hinging scores of the holder members to the end walls to the end edges of the corner flap members and disposed in an inwardly inclined relation thereto, the sections of the corner flaps connected to the holder members having folding scores extending diagonally outward from the hinge connections for the holder members to the end walls, the side walls having folding scores extending diagonally outwardly from their end edges providing folding flaps to which the end wall sections of the corner flaps are secured permitting the side walls being collapsed inwardly upon the bottom and the end walls and holder members collapsed on the side walls, the article holder members when the carton is erected being foldable inwardly between the side walls with their swinging edges on the bottom and acting to hold the carton in erected position.

4. A collapsible carton formed of a cut and scored blank and comprising a bottom, side and end walls hingedly connected to the bottom, article holder members hingedly connected to the outer edges of the end walls and of a width exceeding that of the end walls, and integral corner flaps hingedly connected to the ends of the end walls and holder members, the corner flap members having folding scores extending from the hinging scores of the holder members to the end walls to the end edges of the corner flap members, the sections of the corner flaps connected to the holder members having folding scores extending diagonally outward from the hinge connections for the holder members to the end walls, the side walls having folding scores extending diagonally outwardly from their end edges providing folding flaps to which the end wall sections of the corner flaps are secured permitting the side walls being collapsed inwardly upon the bottom and the end walls and holder members collapsed on the side walls, the article holder members when the carton is erected being springably foldable to an inwardly inclined position between the side walls with their swinging edges on the bottom and acting to hold the carton in erected position.

5. A collapsible carton comprising a bottom, side and end walls hingedly connected to the bottom, article holder members hingedly connected to the outer edges of the end walls, and corner flaps hingedly connected to the ends of the end walls and holder members, the hinge connections for said corner flap members extending in outwardly converging relation from the hinging

70 scores of the side walls to the bottom, the corner flap members having folding scores extending from the hinging scores of the holder members to the end walls to the end edges of the corner flap members, the sections of the corner flaps connected to the holder members having folding scores extending diagonally outward from the hinge connections for the holder members to the end walls, the side walls having folding scores extending diagonally outwardly from their end edges providing folding flaps to which the end wall sections of the corner flaps are secured permitting the side walls being collapsed inwardly upon the bottom and the end walls and holder members collapsed on the side walls, the article holder members when the carton is erected being foldable inwardly between the side walls with their swinging edges on the bottom and acting to hold the carton in erected position.

scores of the side walls to the bottom, the corner flap members having folding scores extending from the hinging scores of the holder members to the end walls to the end edges of the corner flap members and disposed in an inwardly inclined relation thereto, the sections of the corner flaps connected to the holder members having diagonal folding scores, the end wall sections of the corner flaps being foldably connected to the side walls, the holder members being provided with nonaligning article receiving recesses in their edges and with article receiving openings aligned with the recesses of the opposite holder member, the article holder members when the carton is erected being foldable to an inwardly inclined position between the side walls with their swinging edges on the bottom and acting to hold the carton in erected position.

6. A collapsible carton comprising a bottom, side and end walls hingedly connected to the bottom, article holder members hingedly connected to the outer edges of the end walls and of greater width than said end walls, and corner flaps hingedly connected to the ends of the end walls and holder members, the corner flap members having folding scores extending from the hinging scores of the holder members to the end walls to the end edges of the corner flap members, the sections of the corner flaps connected to the holder members having diagonal folding scores and being foldable upon themselves along the diagonal folding scores when the carton is erected, the end wall sections of the corner flaps being foldably connected to the side walls, the article holder members when the carton is erected being foldable to an inwardly inclined position between the side walls with their swinging edges on the bottom and acting to hold the carton in erected position, the corner flaps having the diagonal folding scores being folded upon themselves about said diagonal folding scores to support the article holding members when folded to said inwardly inclined position.

7. A collapsible carton comprising a bottom, side and end walls hingedly connected to the bottom, article holder members hingedly connected to the outer edges of the end walls, and corner flaps hingedly connected to the ends of the end walls and holder members, the hinge connections for said corner flap members extending in outwardly converging relation from the hinging scores of the side walls to the bottom, the corner flap members having folding scores extending from the hinging scores of the holder members to the end walls to the end edges of the

corner flap members, the sections of the corner flaps connected to the holder members having diagonal folding scores, the end wall sections of the corner flaps being foldably connected to the side walls, the article holder members when the carton is erected being foldable to an inwardly inclined position between the side walls, the corner flaps having the diagonal folding scores being folded upon themselves about said diagonal folding scores to support the article holding members when folded to said inwardly inclined position.

8. A collapsible carton comprising a bottom, side and end walls hingedly connected to the bottom, article holder members hingedly connected to the outer edges of the end walls, and corner flaps hingedly connected to the ends of the end walls and holder members, the corner flap members having folding scores extending from the hinging scores of the holder members to the end walls to the end edges of the corner flap members, the sections of the corner flaps connected to the holder members having diagonal folding scores, the side walls having folding scores extending diagonally outwardly from the inner ends of their end edges providing folding flaps to which the end wall sections of the corner flaps are secured permitting the side walls being collapsed inwardly upon the bottom and the end walls and holder members collapsed upon the side walls and preventing collapsing of the side walls outwardly from an erected position, the article holder members when the carton is erected being foldable to an inwardly inclined position between the side walls and into supporting relation with the inner sides of the side walls to prevent inward collapsing of the side walls, the corner flaps having the diagonal folding scores being folded upon themselves about said diagonal folding scores to support the article holding members when folded to said inwardly inclined position.
